UNITED STATES PATENT OFFICE

2,466,630

CLOTHES DRIER

William H. Yandell, Cincinnati, Ohio; Goldia M. Ball, executrix of said William H. Yandell, deceased, assignor, by mesne assignments, to Goldia M. Ball, Mariemont, Ohio

Application April 3, 1944, Serial No. 529,338

4 Claims. (Cl. 68—241)

1

My present invention pertains to means for expressing water from clothing and is intended more particularly for use in connection with clothes washing means.

In the structure of my prior Patent No. 1,993,201, a rubber diaphragm was distended by fluid pressure, either air or water, to cause the water-expressing action. This diaphragm yielded readily to place pressure upon parts of the clothing where the thickness was not sufficient to get a pressure equal to that where the clothing was thicker. While this construction was very satisfactory, it was found that, when air was the pressure medium used, there was a chance for the valve to freeze and the safety mechanism might fail to work. Also, it was felt that too much strain was placed upon the rubber diaphragm in requiring it to be distended so much and so often. Therefore, the present construction has been developed which permits shifting of the pressure medium with only comparatively slight distension of the diaphragm, and yet the pressure effect upon the clothing remains substantially the same as with my prior construction.

Among the objects of this invention are to provide a water-expressing mechanism for a clothes washing machine which will permit the clothes-engaging medium to yield in accordance with the resistance exerted by the clothing so that there will be substantially uniform pressure upon all parts of the clothing, resulting in the clothing having few if any wet spots, the clothing being of substantially uniform dampness when removed from the dryer; to provide a structure of the character indicated in which the chance for accident is reduced to a minimum; to provide a structure of the character indicated in which the amount of distension of the rubber diaphragm is reduced to a minimum; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 represents a horizontal section through a washing machine casing and a dryer in accordance with my present invention, approximately along the plane indicated by the line 1—1,

2

Fig. 2, with certain parts omitted for the sake of clarity;

Fig. 2 represents a transverse section approximately along the plane indicated by the line 2—2, Fig. 1, showing the dryer in elevation, with a part of the dryer casing broken away to expose the internal mechanism; and

Fig. 3 represents a vertical section, approximately along the line 3—3, Fig. 1, this figure being intended to show the internal mechanism of the dryer. The plane of this section is also shown by the line 3—3, Fig. 2.

Reference will now be made in greater detail to the annexed drawings for a more complete description of this invention. The outer casing 1 which encloses the washing machine and dryer is conventional and therefore need not be shown in detail. Within this casing is housed a driving motor 2, and the driving gearing for the washing machine, within the casing, from which rises the dolly shaft 4 of the washing machine. A drive belt 5 connects the pulleys 6 and 7 for transmitting power from the motor 2 to the washing machine gearing. Any conventional means 10 for connecting and disconnecting the driving connection between the motor and the gearing may be provided. All this is conventional and need not be disclosed in detail.

A pulley 8 is mounted on the same shaft with the pulley 6 and is connected to the pulley 9 on shaft 10 by a belt 11. A clutch 12, 13 serves to connect the shaft 10 in driving relation with the pulley 8, the clutch being operated by a bell crank lever 14. This bell crank is actuated by the link 15 connected to and actuated by an eccentric 16 carried by shaft 39b which is connected by suitable means 17 to an operating handle conveniently located near the top of the dryer. Since this handle may be located at any suitable point near the top of the dryer, it is not regarded as necessary that it be shown in detail.

Mounted on the shaft 2a of motor 2 is a water pump 18 which receives water through the pipe 19 and discharges it through the pipe 20 into the washing machine compartment. The pump 18 is of the rotary type and it is apparent that it is in operation whenever the motor is operating.

The shaft 10 also operates a two-cylinder, reciprocating pump 21, as is apparent from Figs. 1 and 2. For this purpose, the shaft 10 comprises a pair of cranks connected by connecting rods 22 to the pistons of the pump 21. Therefore, when the clutch 12, 13 is closed by operation of the bell crank 14, and the motor 2 is running, the two-cylinder pump will be put into operation. It

is clear from Fig. 3 that a trough 23 surrounds the upper end of the dryer which is provided with a loosely fitting removable lid 24 so that when wet clothing is pressed against the lid, the water will pass through the woven open mesh basket 24a fixed to the ring 24b which is removably mounted on the top of the dryer body casing 25, in the manner shown and described in my prior Patent 2,023,215. This water will run out into the trough and will be drained back through the pipe 19 to the pump 18 to be carried back to the washing compartment. The lid 24 together with the open mesh basket 24a form a foraminous cover for the device. Reference will now be made more particularly to Fig. 3 from which it will be seen that the dryer body casing 25 has a container or receptacle 26 extending downwardly therefrom and is provided with a bottom or base 27 which supports all of the operating mechanism within the body 25. The container 26 contains the operating fluid, preferably oil, by means of which the piston 28 is raised. This piston slides in a cylinder 29 which is securely fastened in a depression 30 in the top of the bottom member or base 27, and the cylinder 29 then becomes an integral upward extension from this bottom member. Within the depression 30 in the bottom 27 is an upwardly extending post 31 which serves as a stop to limit the downward movement of the piston 28. Secured to this piston is a sleeve 32 which connects the piston 28 with the upper piston or plunger 33. It is therefore apparent that, when the lower piston is forced upwardly, its upward movement is transmitted to the upper piston 33 which causes pressure upon any clothing within the chamber above the upper piston.

A suction pipe 34 extends downwardly from a valve member 35 controlled by a spring pressed ball 36 in valve opening 36' formed in the base and which prevents return of the oil from the cylinder of pump 21 to the chamber 26. A corresponding valve 37 in valve opening 37' permits oil to be passed from the pump cylinder to the chamber 26 and prevents its return to the pump cylinder upon reversal of motion of the pump piston. A similar valve 38 in valve opening 38' acts as a safety means to prevent building up excessive pressure below the piston 28, this valve being adjusted to open under a definite pressure, as, for example, forty (40) pounds per square inch. Therefore, when the pressure in the chamber 26 exceeds the amount for which the valve 38 is set, then this valve will open and let the oil return to the chamber 26. Usually this does not happen until upward movement of the piston 28 is stopped. Shaft 39b is connected to valve 38 in valve opening 38' and rotates same whenever the handle is operated to open or close clutch 12, 13. Hence, it is clear that the valve 38 is always closed when the pump is operating and always open when the pump clutch is opened to disconnect the pump from the motor. When the driving connection to the pump 21 is disconnected by opening clutch 12, 13, the valve 38 is opened, as shown in Fig. 3, and the oil drains out of the chamber 26 and returns to the chamber 26 through the vent 39a, thus permitting the pistons 28 and 33 to lower.

Pairs of lugs 40 are formed on the upper surface of the bottom 27 and connectors 41 are secured between these lugs. The lower coil of a spring 42 passes through these connectors and is held by them secured to the bottom 27. Similar connectors 41 fasten the upper coil of spring 42

between lugs 40 on the bottom of the upper piston 33. These lugs correspond to the lugs 40 on the top of the bottom plate. As the piston 28 is raised, the spring 42 is extended and, when the piston is permitted to move downwardly, the spring 42 contracts and pulls the upper piston 33 down until the stop 31 acts to discontinue the downward movement. A plurality of holes 44 through the wall of cylinder 29 acts to permit the oil to flow outwardly through the wall into the chamber 26, and from here into the groove 46, from which it flows through a vent or vents 47 to be returned to the chamber 26. A trough 48 is secured inside the dryer wall to catch any water which may escape past the piston 33 and return it through pipe 49 to pipe 19. The holes 44 are provided in order to prevent the pressure-fluid from forcing the pressure piston upwardly far enough to disconnect the piston 28 from the cylinder 29.

The upper surface of the piston 33 is formed with a depression so that it has an upstanding flange 50 around the edge thereof. A flexible diaphragm 51 has its periphery bent down inside of this flange 50 and this edge is then secured in place by means of a ring 52 and screws 54. When these screws are screwed in tightly, this ring holds the edge of the diaphragm firmly against the metal part of the piston 33. The space or pocket 51' within the diaphragm 51 is substantially filled with beads or balls 53, the size of which may vary but which I prefer to have about three-sixteenths of an inch in diameter. On account of the mobility of these balls, they will yield readily to permit the diaphragm 51 to flex into areas of low pressure and therefore there will be substantially even pressure upon all clothing between the diaphragm and the lid 24. This diaphragm is formed with a rib 55 extending horizontally around the same above the upper edge of the flange 50 and into contact with the inner surface of wall 25. Hence, there will be little if any leakage between the piston and the wall. Whatever water passes the piston will be caught in the trough 48 and drained off through pipe 49 into pipe 19 and, as explained above, will pass through pump 18 and pipe 20 to the washing compartment of the washing machine.

Notwithstanding the fact that I have described what is now regarded as the preferred embodiment of this invention, I do not wish to be restricted to the specific invention shown and described herein.

Having now described my invention, I claim:

1. In a washing machine, a fluid expressing mechanism comprising a dryer body casing having a fluid receptacle at its lower portion, a supporting base in said casing fitting tightly therein and separating the receptacle from the interior of the casing, said base having valve openings therein and a compartment, one of said openings having a valve therein allowing upward movement of a fluid from the receptacle toward the casing, another of said openings having a valve therein allowing movement of said fluid in the opposite direction, pumping mechanism in the casing adapted to draw fluid through the first named valve and force it into said compartment, said base having a passageway connecting the pumping mechanism and said compartment, a valve in said passageway, a cylinder connected fixedly with said supporting base, a piston slidable in said cylinder, a second piston above and supported away from the first piston, connecting means rigidly connecting said pistons, a water collecting trough secured to the inside of the casing wall

to catch any water which may escape past the second piston, a drain pipe connected to said trough to carry water collected therein to the exterior of the casing, a trough surrounding the upper part of the casing, a drain connecting the last mentioned trough and the drain pipe and serving to carry water from both to the washing machine compartment, spring means connected to said supporting base and said upper piston to cause lowering of the latter when fluid pressure is discontinued below the piston, and actuating means for the pumping mechanism.

2. In a washing machine, a fluid expressing mechanism comprising a casing having a fluid receptacle at its lower portion, a supporting base in said casing fitting tightly therein and separating the receptacle from the interior of the casing, said base having valve openings therein provided with valves for controlling the flow of pressure fluid through the base, a compartment in said base opening upwardly, pumping mechanism in the casing adapted to draw pressure fluid through one of said valves and force it into said compartment, said base being provided with a passageway between the pumping mechanism and the compartment, a valve in said passageway to control the passage of fluid in one direction through said passageway, a cylinder mounted in and extending upwardly from said compartment, a double-ended elongated piston, one end of which is reciprocable in said cylinder, means for returning said piston toward its lower limit of movement when the pumping mechanism ceases to function, and a readily shiftable pressure medium on the upper surface of said piston which will yield downwardly in areas of greatest resistance to upward movement of the piston.

3. In an apparatus of the nature disclosed for expressing water from clothes and the like in the process of laundering, a cylindrical casing perpendicularly disposed, its upper end having a foraminous cover removably applied and a trough peripherally thereabout for the collection and drainage of liquid expressed from the casing through the foraminous cover, the casing internally at its lower portion having a septum subdividing the same to provide a fluid supply compartment at the base of the casing, a cylinder concentric within said casing supported upon said septum, said septum having a passage between said cylinder and compartment, a valve in said passage, a plunger reciprocable within the upper portion of the casing for compressing the material thereon against said foraminous cover to express the liquid therefrom, a piston reciprocable within said cylinder and in spaced union with said plunger and means for supplying fluid under pressure from said compartment into said

cylinder for imparting an upward power stroke to said piston, the piston retreating upon opening communication between said cylinder and compartment through said passage.

5. 4. In an apparatus of the nature disclosed for expressing water from clothes and the like in the process of laundering, a cylindrical casing perpendicularly disposed, its upper end having a foraminous cover removably applied and a trough peripherally thereabout for the collection and drainage of liquid expressed from the casing through the foraminous cover, the casing internally at its lower portion having a septum subdividing the same to provide a fluid supply compartment at the base of the casing, a cylinder concentric within said casing supported upon said septum, said septum having a passage between said cylinder and compartment, a valve in said passage, a plunger reciprocable within the upper portion of the casing for compressing the material thereon against said foraminous cover to express the liquid therefrom, the upper side of said plunger covered by an elastic cap peripherally compacted against the inner surface of the casing for effecting a liquid seal with the casing about the periphery of the plunger and with the plunger providing a pocket for the plunger area, shiftable elements housed in said pocket to render said cap yieldable, a piston reciprocable within said cylinder and in spaced union with said plunger and means for supplying fluid under pressure from said compartment into said cylinder for imparting an upward power stroke to said piston, the piston retreating upon opening communication between said cylinder and compartment through said passage.
